UNITED STATES PATENT OFFICE.

JOHN M. RICHARDSON, OF MILWAUKEE, WISCONSIN.

DAVENPORT.

1,269,643.

Specification of Letters Patent. Patented June 18, 1918.

Application filed December 29, 1917. Serial No. 209,486.

To all whom it may concern:

Be it known that I, JOHN M. RICHARDSON, a citizen of the United States, and resident of Milwaukee, in the county of Milwaukee and State of Wisconsin, have invented certain new and useful Improvements in Davenports; and I do hereby declare that the following is a full, clear, and exact description thereof.

10. My present invention relates to new and useful improvements in foldable couch beds or davenports, particularly in the mechanism for simultaneously moving the seat and back thereof to expose the bed portion.

15. Heretofore it has been customary to provide a rather complicated mechanism for moving the back of the davenport out of its normal position upon the raising of the seat to expose the bed portion, said back being usually pivoted to the davenport frame as illustrated in my Patent No. 1,198,480, granted September 19, 1916. Such construction necessitates a relatively wide or deep article which is most too wide 20 to be easily movable through ordinary doorways. One object of the present invention, therefore, is to reduce the front to rear width of the davenport and consequently decrease the cost of manufacture and the 25 amount of operating mechanism which has been heretofore necessary.

An additional object subordinate to the foregoing object is to provide a mechanism whereby the normally vertically disposed back may be retained in this position when the davenport is open, yet disposed above the frame and out of the way of the elevated seat.

With the foregoing and other objects in view the invention consists in certain peculiarities of construction and combination of parts as set forth hereinafter.

In the accompanying drawing:

Figure 1 represents a vertical sectional view of a davenport or couch bed embodying the features of my invention, the parts of the same arranged in closed or normal position, and

Fig. 2 is a similar view showing the parts arranged as they will appear when the davenport is used as a bed.

In the embodiment illustrated the numeral 1 designates an end piece of a skeleton davenport or couch bed frame, there being 55 two of the same which are connected by front and rear sills 2 and 3 respectively and a top

rail 4. Between the end piece 1 is disposed a normally horizontal seat A and a substantially vertically positioned back B. When the seat and back are arranged in their normal position as shown in Fig. 1 the folding bed portion C will be hidden from view.

When it is necessary to extend the foldable bed portion C the seat and back are raised as shown in Fig. 2, the means for accomplishing such elevation of these parts being the object of the present invention. Said invention consists of a number of suitably arranged links or levers, one complete set of which is preferably used at each end 70 of the couch frame, although only one set is illustrated. Therefore in the following description of the details of my invention only one set will be referred to.

Specifically the invention comprises an attaching plate or strip 5 of right angular formation, one leg of which is secured to the end piece 1 while the other leg is attached to the top rail 4, an L-shaped link 6, an intermediately pivoted lever 7 and a connecting bar or strip 8. From the drawing it will be noted that the short arm of the L-shaped link 6 is pivoted to the attaching plate 5 adjacent the top rail 4, while the other arm thereof is similarly connected to 80 an attaching plate 9 secured to one end of the back B, said point of connection between the link and the back being substantially midway the top and bottom edges of the latter.

The intermediately pivoted lever is fulcrumed to the attaching plate 9 at a point spaced from the pivotal connection of the link 6 therewith, one end of the lever being pivoted to the attaching plate 9 adjacent the bottom edge of the back B. The other end of the lever is pivoted to one end of the connecting bar 8 which in turn is fulcrumed to a crank plate 10 carried by the seat A. This crank plate also provides the pivotal connection of the seat A with the davenport frame. The pivot of the connecting bar 8 is spaced from the other pivot of the crank plate 10.

In operation the front end of the seat A 105 is raised to rock the same about its pivot, such movement causing the connecting bar to move downwardly and thus rock the lever 7, which lever being pivoted to the back B adjacent its bottom will cause the 110 same to rise upwardly. The L-shaped link 6 retains the back B in substantially verti-

cal position throughout its upward movement and holds the same in this position after it has reached its limit. When the seat A has been moved upwardly to a substantially vertical position the back B will have reached its limit of movement and will then be positioned vertically substantially directly above the upper or front edge of said seat, these parts thereby occupying a very limited amount of space and in nowise interfering with the formation or occupancy of the bed formed by the bed portion C.

An examination of the drawing in this application with that in the patent above referred to will disclose the fact that the frame in this invention may be much narrower than that in said patent. In other words by substituting the vertical arrangement of links and levers for the geared segments shown therein the rear wall 11 of the davenport is quite close to the back B. In actual practice the reduction in width is from thirty-two to twenty-nine inches.

25 I claim:—

1. In a foldable couch bed, a frame, a normally substantially horizontally disposed seat having its rear end in pivotal union with said frame, a substantially vertical back, and means connecting the seat and back whereby when the seat is raised from a horizontal to a vertical position the back will be moved upwardly and disposed vertically above the top or front edge of said seat.

2. In a foldable couch bed, a frame, a normally substantially horizontal seat having its rear end in pivotal union with the frame, a substantially vertical back, a lever pivotally carried by the frame and connected with the back, and a connection between

said lever and the seat whereby when the latter is raised from a horizontal to a vertical position the back will be moved upwardly and disposed vertically above the 45 top or front edge of said seat.

3. In a foldable couch bed, a frame, a normally substantially horizontal seat having its rear end in pivotal union with the frame, a substantially vertical back, a lever pivotally carried by the frame and connected with the back, a link pivotally connected with the back and frame, and a connection between said lever and the seat, whereby when the latter is raised from a horizontal 55 to a vertical position the back will be moved upwardly and disposed vertically above the top or front edge of said seat.

4. In a foldable couch bed, a frame, a normally substantially horizontal seat having its rear end in pivotal union with the frame, a substantially vertical back, a link pivotally connected with the back and frame, a lever fulcrumed intermediate its ends to the frame at a point spaced from 65 the pivot of the link therewith, one end of the lever being pivoted to the back at a point spaced from the pivot of the link therewith, and a connecting member pivoted to the other end of the lever the other end 70 of the member being pivoted to the seat at a point spaced from its fulcrum, whereby when the seat is raised from a horizontal to a vertical position the back will be moved upwardly and disposed vertically above the 75 top or front edge of said seat.

In testimony that I claim the foregoing I have hereunto set my hand at Milwaukee, in the county of Milwaukee, and State of Wisconsin.

JOHN M. RICHARDSON.
